UNITED STATES PATENT OFFICE

CARL F. WOLTERS, OF MARIETTA, OHIO, ASSIGNOR, BY MESNE ASSIGNMENTS, TO REMINGTON RAND INC., OF NEW YORK, N. Y., A CORPORATION OF DELAWARE

INSULATED FILE CABINET

Application filed March 18, 1927. Serial No. 176,517.

This invention relates to file cabinets and has reference more particularly to insulated file cabinets for the reception of index trays.

It is desirable to have index trays for holding overlapping index cards encased in an insulated cabinet which is proof against fire and burglars. The best form of door for such an insulated cabinet is one which is hinged at the bottom so as to swing outwardly and downwardly to horizontal position, in which position the door serves as a support for the ends of the trays when they are moved out of the cabinet and swung downwardly. Due to the heavy insulated construction of the door, trouble has been experienced due to its accidental dropping and breaking loose from its hinges.

An object of this invention therefore is to provide a cabinet for a series of superposed index trays which is insulated and proof against fire and burglars.

Another object of the invention is to provide a cabinet for index trays in which the heavy insulated door is counterbalanced to prevent its breaking from its hinges by accidental dropping.

Another object of the invention is to provide a cabinet for index trays in which the door swings outwardly and downwardly into horizontal position so as to form a support for the outer ends of the index trays.

A further object of the invention is to provide a cabinet for index trays in which the door of the cabinet swings outwardly and downwardly and then is translated under the bottom of the cabinet to reduce the overhang and space occupied by the door.

A still further object of the invention is to provide an insulated tray cabinet in which the insulated door is held in closed position by improved locking means; also to improve cabinets in other respects hereinafter specified and claimed.

Reference is to be had to the accompanying

drawings forming a part of this specification, in which,

Fig. 1 is a front elevation of my improved file cabinet with one door open,

Fig. 2 is a longitudinal vertical section through the file cabinet with a door open,

Fig. 3 is a longitudinal sectional elevation through the file cabinet showing the door counterbalancing device,

Fig. 4 is a fragmentary sectional elevation showing the slide member,

Fig. 5 is a fragmentary sectional elevation through the file cabinet with the door open,

Fig. 6 is a sectional view through the file cabinet on the line 6—6 of Fig. 5,

Fig. 7 is a fragmentary elevation of the cable connection with the cabinet,

Fig. 8 is a perspective view of the cable pulley connections with the counterbalancing springs,

Fig. 9 is a fragmentary sectional view through the door track,

Fig. 10 is a sectional perspective view of a modified form of file cabinet and door,

Fig. 11 is a longitudinal fragmentary sectional view through the file cabinet shown in Fig. 10,

Fig. 12 is a perspective, fragmentary view of another type of door device,

Fig. 13 is a transverse sectional view through the door device shown in Fig. 12,

Fig. 14 is a perspective fragmentary view of still another form of door device,

Fig. 15 is a sectional fragmentary elevation of a cable connection used with the door devices shown in Figures 12, 13 and 14.

Fig. 16 is a plan, fragmentary view of index holders in a tray, and

Fig. 17 is sectional view through the tray shown in Fig. 16.

Referring to the drawings by numerals, 15 indicates the molded case or container of the cabinet, which is preferably composed largely of gypsum from which the free moisture has been expelled by drying. This molded

and dried gypsum still contains about twenty per cent water of crystallization which is released as steam when the molded insulated container is subjected to a severe fire. The 5 gypsum is preferably mixed with a small quantity of sawdust before being poured into molds, so that the resulting cast insulation is not as brittle as it would be without the sawdust.

10 In order to reinforce the molded insulation 15 in case of fire and as a resistance to burglar tools, steel reinforcing members 16 are embedded in the insulation at the time of molding, and this reinforcing may take the form 15 of expanded metal. After the insulation 15 is molded and dried, it is slipped into a specially formed steel or other metal outer shell 17 which is usually coated with baked enamel inside and out. This steel sheet 17 is for the 20 purpose of causing the steam formed in the insulation during a severe fire to be directed into the inside of the file cabinet to reduce the temperature inside the cabinet and prevent charring of the papers and index cards contained therein. The steel shell 17 also gives a 25 pleasing appearance to the outside of the cabinet.

The cabinet may conveniently be formed in 20 duplicate as shown in Fig. 1, with a partition 18 dividing the cabinet into two compartments, each of which is adapted to receive a sheet metal tray cabinet 19 of standard design. This tray cabinet 19 is constructed to receive a series of superposed index trays 20, each of which contains a series of overlapping index cards or card holders 20a having lugs 20b engaging tray flanges 20c as is well known in the art. Each tray 20 has a hinged tail piece 21 which slides in suitable guides 40 in the cabinet 19 and is adapted, when the tray is pulled outwardly to its extreme position, to permit the outer end of the tray to swing downwardly to expose the index cards in convenient position for ready reference.

45 The insulated cabinet 15 has a bottom 22 and an open front side 23. An insulated door 24 is provided at its lower end with a hinge 25 and said door is adapted to normally close the open side 23 of the insulated cabinet 15 so as to prevent the removal of the trays 20 from the cabinets 15 and 19. The door 24 is provided with interfitting flanges 26 which cooperate with flanges 27 on the insulated cabinet 15 to provide a substantially water 50 and gas tight joint and closure for the insulated cabinet 15 in case of fire. One side of the hinge 25 is secured to a slide member 28 which is composed of sheet metal and is provided with rollers 29 slidably received in 55 guideways 30, the latter being secured to the lower face of the cabinet bottom 22.

A suitable lock 31 is provided to maintain the door 24 in closed position. This lock is provided with a disc 32 between the faces of 60 the door 24, and a pair of oppositely disposed

lock bars 33 are pivotally connected to the disc 32 so that when handles 34 of the lock 31 are rotated, the bars 33 will be axially moved in opposite directions so as to take into slots 35 formed in the side walls of the cabinet 15 and maintain said door in closed position. A key may be then inserted in the lock and actuated so as to prevent unauthorized opening of said lock.

When the lock is opened, the door 24 may 75 be swung outwardly and downwardly about its hinge 25 until said door is positioned in a substantially horizontal position. When at this horizontal position, the door may be translated inwardly by pushing on its outer 80 end, which causes the slide member 28 to move inwardly under the cabinet bottom until the rear of said slide member engages a stop 36 at the back of the cabinet. The door may then be in a position as shown in Fig. 2 in 85 which the door does not extend out far enough to occupy an abnormal amount of floor space, but yet extends out far enough to serve as a rest or support for the free end of the trays 20 when they are swung downwardly into 90 reference position. A track 37 is provided on the front surface of the door below the lock 31 which is adapted to slide along a channeled frame 38 of the cabinet 15 so as to prevent marring of the enamel on the front surface 95 of said door 24.

The door 24 is massive in construction because of the fact that it is formed of molded insulation which has considerable weight. The danger exists therefore, that if the door is 100 accidentally dropped from a vertical to a horizontal position, the momentum of the falling door will break it loose from its hinge 25. It is therefore desirable to provide a counterbalancing means for the door 24 to 105 resist its downward movement and prevent any sudden dropping thereof. This counterbalancing means may be of any desired kind, but is preferably of the form shown in Fig. 3, 5, 6, 7 and 8. A steel cable 39 or other flexible 110 member is pivotally secured at one end to the door 24 by means of a bracket 40 secured to said door, said bracket having a stud 41 with an enlarged head. A clip 42 having a bayonet slot 43 is secured to the end of cable 39 in any suitable way such as by soldering 44. This detachable connection of the end of the cable 39 with door 24 makes it possible to 115 easily assemble the cable to said door when under the tension of counterbalancing springs to be hereinafter described. The opposite end of the cable 39 is provided with a clip 42 and is attached to a part of the cabinet 15 by means of a pin 46.

The counterbalancing means associated with the cable 39, in the embodiment shown, consists of a plurality of coil springs 47, each of which is secured at its lower end to a clip or bracket 48 secured to the cabinet 15. The upper ends of the springs 47 are connected to 120

lugs 49 formed on a pulley bracket 50. The bracket 50 has an outstanding flange 51 formed with an aperture 52 through which extends a U-shaped pulley holder 53, the latter having outstanding stop flanges 54 adapted to engage the flange 51 and resist the tension of the springs 47. A pulley shaft 55 extends through the legs of the pulley holder 53 so as to rotatably connect a pulley 56 to said pulley holder 53 and springs 47. A second pulley 57 is rotatably connected to shaft 58 which is secured to the wall of cabinet 15. The pulley 57 is therefore fixed in position while the pulley 56 is movable and the cable 39 intermediate its ends passes over the pulleys 56 and 57 so as to connect up the counterbalancing springs 47 with a block and tackle arrangement. Thus when the lock 31 is opened and the handle 34 rotated, the door 24 will swing downwardly and at the same time the spring 47 will be extended and an increasingly large resisting force will be applied through cable 39 to the pin 41 on door 24 to prevent the sudden dropping of said door. Ordinarily the tension of the springs 47 is so adjusted that normally the door 24 will be held at an angle intermediate the vertical and horizontal by said springs, and it will be necessary for the operator to apply a manual downward pressure to the end of the door 24 in order to cause it to be lowered to horizontal position. When the door is moved to horizontal position, the tension on the cable 39 which then extends at a considerable angle to the vertical, will tend to slide the door to the right as seen in Fig. 5, which also causes the slide member 28 to move to the right with the rollers 29 rolling on guideways 30, until the rear of said slide member is engaged by stop 36.

In the modified form shown in Figs. 10 and 11 the door 24a is hinged directly to the bottom 61 of the cabinet. In order to avoid the use of counterbalancing means, the door 24a is provided with a device to stop its downward movement at an angle of about thirty degrees to the vertical, as shown in Fig. 11, so that further downward movement must be accomplished after release by the operator of the control device. This control device consists of an offset lever or link 62 pivoted at one end to a bracket 63 secured to an edge of the door 24a. The opposite end of lever 62 is provided with a stud 64 which extends outwardly into a cam slot 65 formed in the wall of the cabinet 15a. This cam slot 65 is provided intermediate its ends with a hook 66 which is adapted to engage the stud 64 as said stud slides forwardly so as to check or stop the downward movement of said door in the position shown in Fig. 11 as above described. It is now necessary for the operator to lift the door slightly and then raise the free end of lever 62 and stud 64 until said

stud is released from hook 66, after which the downward movement of the door can be continued under the control of the operator.

Under certain conditions the overhang of the door 24, as shown in Fig. 2, is objectionable because of the floor space which it occupies. However, the slide member 28 in the construction shown in Fig. 2, must be of sufficient length that when the door 24 is fully extended in its horizontal position, little or no side play takes place in the door, which would indicate defective workmanship to a user. For this condition, therefore, it is necessary to shorten the length of the slide member 28, as shown in Figs. 12 and 13, or to provide a collapsing slide member, as shown in Fig. 14.

In the device shown in Fig. 12, the slide member 68 is considerably shorter than the slide member 28 and at its forward end is provided with a hinge shaft 69 passing through suitable loops 70 on the forward end of said slide member 68. Other loops 71 secured to a door 72, shown in dot and dash lines of Fig. 12, also extend around the shaft 69 so as to form a hinge connection between slide member 68 and door 72 and to rotatably support said shaft 69.

Channel tracks 73 are secured to the inside walls of the insulated cabinet 15, said channel tracks being substantially U-shaped in cross section with the legs of the U extending substantially horizontally. The inner edge of each of the lower legs 74 of the channels 73 is provided with an upstanding flange 75, on the upper edge of which is formed rack teeth 76. On each of the outer ends of shaft 69, is rotatably mounted a roller 77, prevented from movement longitudinally of the shaft 69 by a shoulder 78 formed on said shaft on one side of each roller 77 and by a head 79 on said shaft formed on the other side of each roller 77. Inside of each roller 77 is a pinion 80 rigidly secured to the shaft 69, the outer diameter of said pinion being smaller than the diameter of each roller 77, so that the roller 77 will roll on the channel leg or track 74 and position the pinion 80 at such height above the rack teeth 76 that the teeth of said pinion will mesh with said rack teeth 76 without binding. At the rear of the slide member 68 is provided another shaft 81 which is parallel to the shaft 69 and has rollers 82 rotatably mounted at each end so as to roll on tracks 74. It is thus seen that when the door is fully extended and in a horizontal position, side play of the door will be prevented by engagement of the pinions 80 with the racks 76, the pinions being rigidly connected through shaft 69.

In the form of the invention shown in Fig. 14, a folding slide member is shown which is composed of a plurality of cross bars 83 and 84. On the outer ends of each of said bars 83 and 84 are rotatably mounted rollers

85 which are adapted to roll in a track 86 formed on U-shaped track members 87 which are similar to members 83 except that the upstanding flange 88 is not provided with 5 rack teeth and serves merely to confine the rollers 85 on the tracks 86. The bars 83 and 84 are connected by lazy tong links 89, said links being preferably four in number and being connected at one end to one of the bars 10 83 or 84 while the other ends of said links are pivoted together in pairs by means of pins 90. A cross link 91 is also pivotally connected to links 89 by the pins 90 so that when the bars 83 and 84 are moved together, 15 the links 89 fold up and the link 91 moves transversely of the track members 87.

A similar set of lazy tong links 92 is provided, which is similar to the lazy tong links already described, except that one end of one 20 pair of links 93 is pivotally connected by pins 94 to the rear wall 95 of the insulated cabinet. It should be understood that the door of the cabinet is hingedly mounted to the bar 83 by any suitable hinge member, not 25 shown. When the door is fully extended in a horizontal position, the bars 83 and 84 will be separated at their maximum distance and when the door is moved rearwardly underneath the bottom of the insulated cabinet, the 30 bars 83 and 84 will move together and approach the rear wall 95 of the cabinet in folded position so that only a few inches of the door will extend beyond the outer face of the cabinet and very little floor space will 35 be then occupied by said door.

In the forms of the invention shown in Figs. 12, 13 and 14, it is necessary to connect a cable 96 to the outer end of the door 72 by means of a pin 97 so that said door may 40 slide back beneath the bottom 98 of the cabinet without interference by the end of said cable. In order to permit the door to swing outwardly and downwardly about its hinge member 99, it is necessary to provide 45 a greater length of cable 96 than that necessary for the device shown in Figs. 1, 2, 3 and 5 because of the fact that the pin 97 swings through an arc of greater radius than the pin 41. Accordingly, two fixed pulleys 100 are 50 rotatably mounted to the upper end of the cabinet and two movable pulleys 101 are rotatably mounted on a double pulley bracket 102. A plurality of coil springs 103 are connected at their ends to the bracket 102 and 55 at their lower ends to a bracket fixed on the cabinet. The bracket 102 may be divided into two parts, if so desired, so that each of the pulleys 101 may move independently of the other. By this block and tackle arrangement, sufficient cable is provided for passing 60 around the four pulleys 100 and 101 to permit the door 72 to swing downwardly and outwardly.

It is thus seen that a fire and burglar proof 65 cabinet is provided for the reception of index

trays and the door of said cabinet is properly controlled by counterbalancing or other means to prevent its sudden dropping and breakage from its hinges. The door is also permitted to slide under the cabinet a 70 limited amount to reduce the ordinarily abnormal amount of overhang and to place said door in a position for conveniently supporting the ends of trays in reference position. The door is also locked securely in a vertical 75 position so that the trays may not be removed from their cabinet by unauthorized persons or in case of fire.

I would state in conclusion that while the 80 illustrated examples constitute preferred embodiments of my invention, I do not limit myself precisely to the details herein described, since manifestly the same can be considerably varied without departing from the spirit of the invention as defined in the appended claims.

Having thus described my invention, I claim as new and desire to secure by Letters Patent:—

1. A fire resisting filing cabinet comprising 90 a container having a plurality of heat insulating walls, one of the sides of the container being open, a heat insulating door mounted on the container to close said open side and being movable to open said open side, co-operating means on said container and on said door engageable when the door is closed to seal the container, and counter-balancing means mounted within the container and connected to the door for both resiliently retaining the door in sealing relation with the container and counter-balancing the weight of the door when opened.

2. A filing cabinet comprising a container 105 of heat insulating material having a plurality of walls, forming a compartment therein, one of the side walls being open and one of the walls of the container adjacent said open side wall having an interior recess opening to said open side, a counter-balancing mechanism 110 mounted in the recess of the side wall, an insulated door mounted on the cabinet for upward hinging movement to close the open side, means connecting the door to the counter-balancing mechanism, said door being movable under aid of the counter-balancing mechanism to close the open side of the container and also the recess in said side wall to seal 115 said compartment and enclose the counter-balancing mechanism and connecting means 120 therein.

3. A filing cabinet comprising a container having a plurality of walls forming a compartment, one of the side walls being open, a door normally closing said open side, said door being hinged adjacent said open side so that the top of the door may be pivoted to a horizontal position, said door having sliding connections with said container whereby said door may be moved under said container when 125

in a horizontal position, a peripheral sealing flange and groove on the door and a cooperating flange and groove on the container, a counter-balancing mechanism within the compartment connected to the door to substantially counterbalance the weight of the door to protect the lower portions of the cooperating flanges, said counter-balancing mechanism also resisting the arcuate swinging movement of the door during opening operation.

CARL F. WOLTERS.
